UNITED STATES PATENT OFFICE.

WARREN B. STUBBS, OF ST. LOUIS, MISSOURI.

HOUSING UNIT FOR RAILWAY WORKERS.

Application filed January 29, 1920. Serial No. 355,006.

To all whom it may concern:

Be it known that I, WARREN B. STUBBS, a citizen of the United States of America, and a resident of the city of St. Louis and 5 State of Missouri, have invented certain new and useful Improvements in a Housing Unit for Railway Workers, of which the following is a specification.

The primary object of this invention is 10 to provide an improved housing system for railway workers which is comprised of a series of coupled together vehicles forming a unit, in which is contained the essential elements necessary for the boarding and 15 care taking of a work crew, provision being also made whereby the series of vehicles comprising the system can be moved intact from place to place.

Another object of the invention is to have 20 the system or equipment comprised of a series of cars arranged in order as follows: a detachable tank car for containing a water supply, a boiler and bath house car in which may also be contained the kitchen and dining compartment, and one or more bunk or sleeping cars, all of which may be steam heated from a heating system cooperative with the boiler of the second car above mentioned.

30 A further object is in providing an improved form of hose connection between the cars so that freezing of the supply pipes will be prevented, in which the system will not be impaired during the cold months of 35 the year.

Other and further objects will appear in the specification and be specifically pointed out in the appended claims, reference being had to the accompanying drawings exemplifying the invention, and in which,

40 Figure 1 is a side elevation showing a series of coupled together cars, each car containing elements that are essential to this improved housing unit and showing the improved supply pipe connection mounted between the adjacent pairs of cars.

Figure 2 is a plan view of the series of cars shown in Fig. 1.

45 Figure 3 is an enlarged fragmentary vertical section of portions of a pair of adjacently located cars showing the supply connecting element, said figure being taken approximately on the line III—III of Fig. 2.

50 Figure 4 is a transverse section taken on the line IV—IV of Fig. 3.

Figure 5 is an enlarged horizontal section taken on the line V—V of Fig. 4.

Referring to the objects of this invention and to the showing contained in the drawings, the main intent of the invention is to 60 provide an improved housing system or unit for track hands generally working in outlying districts, the manner of housing labor heretofore being done in a make shift way such as furnishing a side tracked box car, 65 serving as a bunk car, and the cooking for the crew generally being done outdoors.

In this connection the invention is comprised of the coupling together of a series of cars forming a housing unit, in which a 70 tank car A containing a water supply is arranged at one end of the series of cars, and the next in order to the tank car is a boiler car B, and coupled with the boiler car is a bunk or sleeping car C, and if desired, any 75 number of other bunk cars D can be provided.

Referring in detail to the drawings, the tank car A comprises a platform 1 which has compartments 2 and 3 located at each 80 end beneath the platform, said tank car having the usual train couplings 4, and as shown in Figs. 1 and 2, one of the couplings 4 is in coupling relation with the coupling 5 of the car B.

Arranged beneath one end of the platform 6 of the car B is a compartment 7, and at the opposite end beneath said platform is a compartment 8, the compartment 7 as shown being adjacent the compartment 3 of 90 the tank car A.

Secured to the under side of the transverse bolster 9 of the car B is a depending carrier 10, and arranged beneath the bolster 11 of the tank car A is a depending carrier 95 12, each of the carriers 10 and 12 having a pair of opposing vertically arranged guide ways 13 formed therein, and resting on the bottom 14 of each carrier is a bushing 15, each of said bushings having a pair 100 of opposing curved walls 16 and a recess 17 adjoining each pair of walls.

Mounted above each of the bushings 15 and adapted to vertical movement in the pairs of opposing guideways 13 of the respective carriers 10 and 12 is a retaining bushing 18, and horizontally arranged above each bushing is a bolt 19. These carriers 10 and 12 of the respective cars B and A are adapted to retain the ends 20 of a tubu- 110

lar connecting member 21, said ends 20 of said member being seated between respective pairs of carriers 10 and 12, and in which one end 20 of the member 21 will extend into the compartment 3 of the tank car A, whereas the opposite end 20 of said member 21 will extend into the compartment 7 of the car B.

Formed on the underside of the tubular member 21 adjacent each end 20 thereof is a stop lug 22, and extending the length of said tubular member between said lugs is a guiding rib 23, said rib being engaged in the recesses 17 of the bushings 15 of each of the carriers 10 and 12.

Adjustably mounted on the tubular member 21 adjacent the longitudinal center thereof is a pair of collars 24, and mounted over said member 21 adjacent each of the carriers 10 and 12 is a seating plate 25, and mounted on said member 21 between each collar 24 and plate 25 thereof is a coil spring 26.

Secured inside of said tubular member 21 adjacent each end 20 is a pipe supporting plate 27, and passing longitudinally through said member are a series of supply pipes 28, and mounted on the ends of each of said pipes is a coupling 29, said couplings at one end of said pipes being for connecting said pipes with a series of flexible hose connections 30, one of said flexible hose connections leading to a water intake pipe 31 which is under the control of a valve 32, said valve being in communication with the water supply of the tank 32 of the tank car A, whereas the remaining hose connection 30 communicates with the return steam pipes 33 which pass inside of the tank 32 adjacent the bottom thereof.

The pipe couplings 29 located at the opposite ends of the supply pipes 28 communicate with a series of flexible hose connections 34, said connections 34 leading to a like number of supply pipes 35 which are located in the boiler car B, said pipes 35 being in communication with the boiler 36 located in said car B. From the aforesaid detailed description, it is to be noted that supply connection is made between the tank car A and boiler car B, in which water can be drawn from the tank car through the intake pipe 31 to the boiler 36 of the boiler car B, and after the water has been acted on by the boiler 36, a hot water supply is then entrained to the succeeding cars C and D through the agency of the pump 37 located in the boiler car B, as the supply connecting element containing the supply pipes such as illustrated relative to the tubular member 21 is located between each pair of cars so that steam as well as hot water can be furnished to the cars C and D. In this connection relative to supplying the cars B, C and D with hot water and steam, as well

as cold water if desired, and relative to the sanitary taking care of the housing of a work crew, a shower bath 38 can be furnished in the boiler car as well as a series of bath tubs 39, and a sterilizing vessel such as 40, whereas in the cars C and D which are steam heated through the agency of the piping system leading from the boiler car and the radiators 41, bunks such as 42 are provided as well as a number of wash basins 43, and if desired, an extra car or part of one of the cars such as C and D can be equipped as a dining room.

Referring again to the showing in Fig. 3 of the drawings, the steam supply to the tank 32 of the tank car A and return steam pipes 33 are for the purpose of maintaining heat in the tank so that the water contained therein will be kept at a temperature above freezing point during the winter months, and since a connecting element such as the tubular member 21 is provided between each pair of cars, each connecting element being in communication with a pair of compartments such as 3 and 7, provision is thereby provided whereby the supply pipes and hose connection contained in and leading from the respective tubular members 21 will be prevented from freezing, as an improved housing unit or system of this character is very likely to stay for months in one locality, and even while the system or unit is being transported from place to place, the series of cars consisting of the coupled together arrangement as described, would be moved intact so that proper housing will be given to the workmen during transportation.

In carrying out the operation of this improved housing system in which the water supply is one of the main essentials to be considered, assuming that the system or unit is side tracked during operations of the workmen in the vicinity, and it is found that the water supply of the tank car A is getting low, a call is then put in for a water supply, and in answer thereto another tank car containing a water supply will be brought up to the system and the emptied tank car will be disconnected and the filled tank car will be coupled in connection with the boiler car B. In disconnecting the tubular member 21 containing the supply pipes from the tank car or any other car, the bolt 19 of the carrier of the car being disconnected is removed so that the bushing 18 can be elevated above the member 21, then the adjacent end 20 of the member 21 is elevated so that the stop lug 22 of said end 20 can pass through the lower bushing 15 as the detaching car is being withdrawn, the pipe couplings 29 however being disconnected before the withdrawal of the car being detached has been made.

During transportation of this improved housing system, or unit from place to place,

the coming together movement between a pair of adjacent cars will be taken care of on account of the tubular members 21 being slidably mounted in their respective carriers, and in which equalization of the longitudinal travel of the members 21 will be effected through the springs 26, and in which the lugs 22 carried by the underside of the member 21 will prevent the ends of said member from being withdrawn from their respective compartments.

In order to take care of the swinging thrust given to the members 21 relative to travelling on curves on the trackway, the angular faces 44 of the bushings 15 and 18 will provide for a swivel connection so that the ends of the member 21 will be allowed to swing therein, see Fig. 5.

When the tubular member 21 of the end cars are not in use relative to being coupled with an adjacent car, the tubular member can be moved rearwardly into the compartment of the end car, in which the end of the tubular member opposite to the end in the compartment will extend therefrom.

What I claim is:

1. A connecting element related to a pair of coupled together cars comprising a single tubular member having its ends slidably extending into portions of each of the cars, said member containing a series of supply pipe connections.

2. A connecting element related to a pair of coupled together cars adapted to longi-

tudinal and transverse movement, each car being provided with a closed compartment, said element at its ends extending into a respective one of said compartments, said element containing a series of supply pipe connections.

3. A connecting element for a pair of coupled together cars comprising a single slidably mounted longitudinally arranged tubular member having its ends extend into portions of said cars, equalizing means mounted on said member for tending to hold said member in neutral position relative to its longitudinal movement between the cars and supply pipe passageways located in said member.

4. The combination of a pair of cars each having a relatable coupling, a single longitudinally arranged tubular member located on a plane beneath said couplings, the ends of said member extending into portions of each of said cars, and a series of supply pipe connections located in said member.

5. The combination of a pair of cars each having a relatable coupling, a longitudinally arranged tubular member located on a plane beneath said couplings, a closed compartment located beneath the floor of each of said cars, each end of said member extending into respective compartments, and a series of supply pipe connections located in said member.

WARREN B. STUBBS.
